JOHN TREMPER, OF WILMINGTON, DELAWARE.

Letters Patent No. 74,454, dated February 11, 1868.

IMPROVEMENT IN STEAM-GOVERNORS.

The Schedule referred to in these Letters Patent and making part of the same.

TO ALL WHOM IT MAY CONCERN:

Be it known that I, JOHN TREMPER, of Wilmington, in the county of New Castle, and State of Delaware, have invented a new and useful Improvement in Governors, of which the following is a full, clear, and exact description, reference being had to the accompanying drawing forming part of this specification, and in which—

Figures 1 and 2 represent partly sectional elevations of a governor constructed according to my improvement.

My invention consists in a novel construction of governor, embracing balls which, in their outward action, radiate or diverge from their centre of motion, or revolving vertical shaft, along guiding-arms or rods, said balls being hinged or pivoted by braces to a collar connected with the valve-rod, and controlled in their action by springs of spiral or other form. Also, in combination therewith of separately-detachable springs, whereby the velocity may be increased or decreased at pleasure, to adapt it to the character of work to be performed.

Said invention, likewise, further consists in a combination of sliding thimbles or sleeves, with the spiral springs arranged to act on the balls, to relieve the latter, or shafts on which they slide, of friction or rub of the springs in the working of the balls; likewise in certain novel arrangements of the springs.

Referring to the accompanying drawing, A represents the main revolving or vertical driving-shaft of the governor, and B the rising and falling valve-rod sliding therethrough, and carrying at or near its top a collar, C, and, it may be, cap or other mounting. D is the hub of the shaft A, from which radiate arms, rods, or shafts E E, on which the balls F F are hung to slide. These balls are connected by braces G G, in a hinged or free manner with the collar C of the valve-rod, and have their action, and that of the valve-rod, controlled by springs, that may be arranged as follows: Thus, there may be a spiral spring, H, arranged to hug the shaft A; and made to bear on the hub D, and under the collar C of the valve-rod, and flat or bow-springs I I, of which any desired number may be used, the same being made to toe or gear with, at their ends, in a loose manner, by entering grooves a b in the collar C and hub D, so that they may be readily attached and detached, or be replaced by other springs of different strength, to suit a varied speed or any required action of the governor. The balls are constructed with tubular projections c c, between the inner ends of which, and (say) grooved collars fast on the ends of the arms E E, the springs J are arranged to bear or press, the same surrounding the arms or shafts E E, and lying within the balls. Each or all of these several spring arrangements or attachments exercise the same control or effect on the governor, and either of such may be used, separately or in combination with one another, or all together, the centrifugal force produced by the governor operating to throw out the balls against the action of the springs. In case of the springs J being used, it is preferable to provide the arms E E with one or more loose sliding-sleeves or thimbles, K, around which the springs J are wrapped, to prevent the springs from catching and producing irregular or excessive friction on the rods or shafts E E, or interior of the balls, as in bending, during the backing or falling of the balls, they would be apt to, said sleeves K serving to keep the springs straight in their action, and to make the rub or friction on the rods E E light and uniform, by taking off the rub or friction of the springs thereon. There may be two or more of these thimbles K on each of the rods E E, so as to form guides or bearings throughout the greater portion of or at different points in the length of the springs, or these latter may be made in sections and slipped over opposite ends of a sliding thimble provided with a dividing-collar. Such alterations, however, involve no radical change, the peculiar construction and action of the governor remaining substantially the same, combining efficiency and facility of varying the speed or power with cheapness, simplicity, and compactness, and essentially differing from other governors using flat or spiral springs, such, for instance, as those employing pendent or swinging balls. By the arrangement of the springs J within the balls, they are both concealed and protected.

What is here claimed, and desired to be secured by Letters Patent, is—

1. The combination of one or more sliding thimbles or sleeves K with the radial or guiding-arms E, springs J, and balls F, substantially as and for the purpose specified.
2. The arrangement of the springs J within the balls F, and their extensions c, encircling the radial or guiding-arms E, essentially as shown and described.
3. The auxiliary removable springs I, for operation in combination with the balls F and springs J, whereby the velocity may be increased or decreased at pleasure, substantially as specified.

JOHN TREMPER.
